UNITED STATES PATENT OFFICE

158,077

COMBINED TOY ANIMAL FIGURE AND CONTAINER OR SIMILAR ARTICLE

Allan S. Jarvis, Los Angeles, Calif.

Application November 17, 1947, Serial No. 142,571

Term of patent 14 years

(Cl. D34—2)

To all whom it may concern:

Be it known that I, Allan S. Jarvis, a citizen of the United States, and a resident of the city of Los Angeles, in the county of Los Angeles and State of California, have invented a new, original, and ornamental Design for a Combined Toy Animal Figure and Container or Similar Article, of which the following is a specification, reference being had to the accompanying drawing, forming part thereof, in which:

Fig. 2 is a side perspective view thereof; and

Fig. 3 is a top plan view thereof.

I claim:

The ornamental design for a combined toy animal figure and container or similar article, substantially as shown.

ALLAN S. JARVIS.
